C. C. HERRELL

ANTIFREEZE VENT FOR PUMPS

Filed Nov. 3, 1922

Inventor
Claude C. Herrell

By *A. J. O'Brien*
Attorney

UNITED STATES PATENT OFFICE.

CLAUDE C. HERRELL, OF VONA, COLORADO, ASSIGNOR OF ONE-FOURTH TO CHARLIE H. DAVIS AND ONE-FOURTH TO WILLIAM O. DAVIS, BOTH OF KIOWA, COLORADO.

ANTIFREEZE VENT FOR PUMPS.

Application filed November 3, 1922. Serial No. 598,816.

To all whom it may concern:

Be it known that I, CLAUDE C. HERRELL, a citizen of the United States, residing at Vona, in the county of Kit Carson and State 5 of Colorado, have invented certain new and useful Improvements in Antifreeze Vents for Pumps; and I do declare the following to be a full, clear, and exact description of the invention, such as will enable others skilled 10 in the art to which it appertains to make and use the same, reference being had to the accompanying drawings, and to the characters of reference marked thereon, which form a part of this specification.

15 This invention relates to pumps of the type employed in raising water from deep wells or cisterns.

In the country and on ranches and farms generally the water for the house and for 20 the stock is usually obtained from wells of varying depth by means of pumps operated by windmills or gas engines. In the western part of this country where cattle raising is conducted on a large scale, the ranges are 25 usually provided with wells and drinking tanks. Windmills are employed to operate the pumps and automatic means is often provided for the purpose of turning off the windmill when the tanks are full and for 30 turning them on again when the tanks are partly emptied. Such watering stations may be located many miles from the ranch houses and are frequently left for several days and sometimes weeks without being 35 inspected.

In order to prevent the pumps from freezing in winter, it is customary to provide a 40 vent hole in the pump pipe sufficiently far below the surface of the ground to insure that the water will not freeze. When the 45 pump stops for any reason, the water above the vent will automatically drain out of that portion of the pipes above the vent, thus preventing freezing. The vents being left 50 open while the pump operates permits a comparatively large amount of water to escape and therefore lowers the efficiency of the pump. Besides the large amount of water that is permitted to flow out through 55 the vent, the stream of water issuing therefrom impinges on the side of the well and causes the same to crumble and cave in, unless the well is cased, and even then damage is done by the stream of water impinging on the walls thereof, as the constant strain to

which it is subjected causes the casing to fail and permits the stream to strike the earth sides and cause damage.

It is the object of this invention to provide a safety device for pumps having means 60 that will close the drain vent when the pumps operate and open the same when the pump stops. It is also my intention to so arrange the vent opening that the water issuing therefrom will strike the pipe of the 65 pump and not the casing. I also desire to provide means which will prevent foreign matter which may be introduced into the upper end of the pump from reaching the cylinder where it might become entangled in 70 the valves and make it necessary to pull the pump.

I attain the above objects and others which will appear as the description proceeds, by means of a construction which I 75 will now describe in detail, reference being had for this purpose to the accompanying drawing, in which

Fig. 1 is a vertical section of a well showing a pump in place therein;

Fig. 2 is a side elevation of the base of a windmill tower and the pump head, and shows how the wire controlling the vent can be connected to the central lever of the windmill so as to secure automatic operation of 85 the valve; and

Fig. 3 is a side elevation of my improved safety device, with parts thereof in section to better show the construction.

The same reference characters will be employed to designate the same parts throughout the several views.

In the drawings I have shown a well 5 which may be of any depth and may be either a dug well or one that has been formed by a 95 well drilling machine. A pump head 6 is put in place on a suitable platform 7. The usual pipes 8 extend from the pump head into the well and terminate near the bottom thereof in a strainer 9. A cylinder 10 of the 100 usual type is connected in the pipes at a point a short distance below the water level. A sucker rod 11 connects the sucker within the cylinder 10 (not shown) with the end of the pump handle 12 in the ordinary manner. As I am employing an ordinary pump whose construction is well known, I shall not describe the same in detail but shall limit my description to my improvement. At a 105 point sufficiently far below the surface of 110

the ground to insure that the temperature will never fall below the freezing point of water, I connect in the line of pipe 8 my improved safety device, which consists of a 5 tubular casing 13 to the ends of which I secure caps 14 and 15, each of which has a central hub 16 which is internally threaded so as to receive the threaded ends of pipes 8. A strainer 17 is secured to a base member 18, 10 which is threaded into the upper end of hub 16, as shown in Fig. 3, and the sucker rod 11 extends through the center of the strainer in the manner shown. It is evident that the strainer will prevent stones or other 15 foreign matter that might accidentally or otherwise be inserted into the upper end of pipes 8, from reaching the cylinder 10.

In the horizontal flange of the lower cap 14, I provide an opening into which I screw 20 a tubular member 19 which serves as a drain or vent for that portion of the pipes which is located above this point. If pipe 19 were left open at all times, it is evident that a portion of the water raised by the 25 pump would escape and that as soon as the pump stopped functioning the pipes above the vent would become drained. As a large quantity of water can escape through an opening of the size of the one in pipe 19, it is 30 my intention to provide means for closing the same when the pump is operating and for opening it when the pump stops. My valve is made and operated as follows: A cartridge-like cap member 20 is slidably connected to pipe 19 and is provided at its lower end with a flange 21 between which and the lower side of cap 14 a coil spring 22 is placed. Coil spring 22 is compressed and tends to move the cap 20 downwardly. A 35 ball 23 is carried in the lower end of cap 20 and is adapted to close pipe 19, whose lower end is chamfered to receive the same. An opening 24 is provided in the cap 22 for the purpose of permitting the water to flow 40 out in the direction of pipe 8. In order to be able to open and close the valve, I connect to the flange 21 a wire 25, which passes through a suitable opening in the flange of cap 14 and extends to a point above the 45 surface of the ground, where, if the pump is hand operated, it is secured to a lever 26 pivoted to the pump head. Two pins 27 are provided and the end of the wire 25, which is formed into a loop 28, is hooked onto the 50 upper one when the valve is to be closed and to the lower one when it is open. The wire 25 is preferably provided with an enlargement 29, which engages the upper edge 55 of the flange of cap 14 and limits the downward movement of the cap 20. Where the 60

pump is operated by a windmill, as indicated in Fig. 2, I connect the upper end of wire 25 to the lever, by means of which the windmill is thrown into and out of gear. When the mill is to operate, the lever 30 occupies the full line position, and when the mill is out of gear the lever 30 is in the dotted line position. A coil spring 31 connects the upper end of wire 25 with the lever 30. The wire 25 is connected to lever 30 in such a 65 position that the valve can open when the lever is in dotted line position and will be closed when the lever is in full line position. By the means just described, the valve controlling the vent will automatically be 70 closed when the windmill is thrown into gear and opened when the windmill is stopped, thus assuring the best efficiency of operation and that the pipes will always be drained when the pump stops. By incorporating my 75 valve in the part containing the screen 17, I provide a unitary safety device that can be incorporated in the pipe line of any pump without changing the latter in the least.

Having now described my invention, what 80 I claim as new is:

1. A safety device for pumps comprising a tubular section, a cap threadedly connected to each end thereof and adapted to connect said tubular section to the pump pipe so that it will be incorporated therein, a vent in one of said caps, said vent having a tubular member secured therein, a valve member slidably connected to said tubular member, means carried by the valve member for closing the opening in the tubular member, a spring surrounding said tubular member and engaging the valve member for holding the latter in open position and means for moving the valve member to closed position. 90

2. A safety device for pumps comprising in combination a tubular section, a cap threadedly connected to each end of said section and adapted to connect said tubular section to the pump pipe so that it will be incorporated therein, an opening extending through one of said caps, a pipe in said opening, a tubular cap member slidably connected to said pipe, a ball carried by said cap member and adapted to close the end 100 of said pipe, a spring surrounding said cap member and having its ends abutting against said cap member and adjacent cap, whereby the cap member is urged in a direction 110 to open the pipe and means connected to said cap member for moving the same against the tension of the spring and for closing the pipe. 115

In testimony whereof I affix my signature.
CLAUDE C. HERRELL.
